UNITED STATES PATENT OFFICE.

CAROLINE W. DIEHL, OF WASHINGTON, DISTRICT OF COLUMBIA.

DESIGN FOR A STATUETTE.

41,050.

Specification for Design. Patented Dec. 20, 1910.

Application filed October 19, 1910. Serial No. 588,001. Term of patent 7 years.

To all whom it may concern:

Be it known that I, CAROLINE W. DIEHL, a citizen of the United States, residing at 1525 P street northwest, in the city of Washington, District of Columbia, have invented a new, original, and ornamental Design for Statuettes, of which the following is a specification, reference being had to the accompanying drawing, forming a part thereof.

The figure is a perspective view of a statuette showing my new design.

I claim:

The ornamental design for a statuette as shown.

CAROLINE W. DIEHL.
